DRIVE MECHANISM

George W. Grisdale, Chicago, Ill., assignor to
 Republic Flow Meters Company, Chicago, Ill.,
 a corporation of Illinois

Application January 21, 1935, Serial No. 2,649

11 Claims. (Cl. 192—12)

This invention relates to one-way drive mechanism and more particularly to mechanism of this type for use in measuring instruments in which it is desired to drive a rotatable driven member 5 from an oscillating driving member.

The mechanism of the present invention is particularly adapted for use to operate a totalizer for a measuring instrument in which a driving member is given a periodic oscillating movement 10 whose amplitude depends upon the quantity to be measured during a given period and which movements are to be totaled by rotating a driven member to indicate the total quantity. Such an instrument is shown, for example, in the copending application of Otto T. Handwerk, Serial No. 5,779, filed February 9, 1935.

In instruments of this character it is highly important that the full amplitude of movement of the driving member shall be transmitted to 20 the driven member in order that the indicated total shall be correct. Thus it is essential that a one-way drive shall be employed between the driving and driven members in which lost motion is reduced to a minimum and which is positive and reliable in its action.

It is accordingly one of the objects of the present invention to provide a one-way drive in which lost motion is reduced to a minimum, which is positive and reliable in its action and 30 which is simple and cheap to manufacture.

According to one embodiment of the invention, a rotatable flanged driven member is provided and an oscillating driving lever is pivoted coaxially therewith. The driving lever has secured to its free end a second lever which has a 35 notch receiving the flange, the two levers being connected together by a leaf spring. Thus when the driving lever oscillates in one direction the notch binds on the flange and rotates the driven member while oscillation of the driving lever in the other direction permits the notch to slide on the flange.

A similar notched lever is mounted on a leaf 45 spring secured to a stationary part and is so arranged that its notch will release the flange and permit movement of the driven member when the driving lever tends to rotate it but will bind to prevent reverse rotation of the driven member.

Other objects, advantages and novel features will appear from the following detailed description when taken in connection with the accompanying drawing showing one embodiment of the 50 invention.

In the drawing wherein like reference numerals refer to like parts throughout the two views:

Figure 1 is a perspective view of a one-way drive device constructed according to the present invention; and

Figure 2 is a partial plan view with parts in section of the device of Figure 1.

In the embodiment illustrated in the drawing, an oscillating driving shaft 10, which may be driven by the measuring instrument shown in 10 the application of Otto T. Handwerk referred to above, has a lever 12 secured thereto to oscillate therewith. The lever 12 has a flange 14 turned up at its free end and a leaf spring 16 is secured to this flange by any suitable means such as 15 rivets or the like.

To the free end of leaf spring 16 is secured a lever 18 having a notch 20 adjacent its free end, for a purpose to appear hereinafter.

The mechanism described above constitutes a 20 driving means and is adapted to drive a rotatable driven member 22 mounted on a suitable shaft 24 which is coaxial with the driving shaft 10. The driven member is preferably provided 25 with gear teeth 26 for connection with a suitable totalizing device, not shown, and a peripheral, axially extending flange 28. As shown, this flange is received within the notch 20 and the lever 18 is so arranged that a radius from the axis of rotation through its point of contact with 30 the flange forms an angle of less than 180° therewith.

In operation of the device as so far described, when the lever 12 swings in a clockwise direction as viewed in the drawing, lever 18 moves to the 35 full line position of Figure 2 in which it is more nearly aligned with a radius from the center of rotation and the flange 28 can slip through the notch 20. When, however, lever 12 swings in a counterclockwise direction, lever 18 assumes 40 the dotted position of Figure 2 in which the corners of notch 20 bind on flange 28 and turn the driven member with the driving lever. Thus the driven member is rotated with the driving member in a counterclockwise direction but, the 45 driving member moves relatively to the driven member in a clockwise direction.

In order to prevent undesired reverse rotation of the driven member, a suitable one-way device is provided to permit rotation thereof in a counterclockwise direction but to prevent rotation in a clockwise direction. As shown, this device is constituted by a notched lever 30 similar to lever 18 and secured to a leaf spring 32 which is carried by a suitable stationary bracket 34. This 55

lever is so arranged that when the driven member is moved in a counterclockwise direction the flange 28 will slip through the notch therein, but if the driven member tends to move in a clockwise direction, the notch will bind and hold the driven member against rotation. By this means the driven member is held against undesirable clockwise rotation under the influence of friction in the driving mechanism.

10 Thus by the present invention there is provided a one-way drive device which is simple in construction, positive and reliable in operation and in which lost motion is reduced to a minimum.

While only one embodiment of the invention 15 has been shown and described, it will be apparent that the same is susceptible of various changes and it is not intended that the scope of the invention shall be limited to the exact form shown nor otherwise than by the terms of the appended 20 claims.

What is claimed is:

1. A one-way drive device comprising an oscillating driving member, a lever connected thereto to be driven thereby, a driven member to be 25 rotated in one direction only, a leaf spring secured at one end to said lever and extending therefrom, a member secured to said spring at its other end and engaging said driven member and so constructed and arranged as to grip said 30 driven member when the lever is moved in one direction but not when the lever is moved in the other direction, said gripping member engaging solely said leaf spring and said driven member whereby the spring flexes to permit the gripping 35 member to grip and to release the driven member, and means secured to a stationary part and engaging said driven member to prevent rotation thereof in one direction but to permit rotation thereof in the other direction.

40 2. A one-way drive device comprising an oscillating driving member, a lever connected thereto to be driven thereby, a leaf spring having one end attached to said lever, a driven member to be rotated in one direction only, said driven member having a peripheral flange, a member 45 fixedly secured to the other end of said spring and engaging said flange, said lever and spring being so constructed and arranged as to grip the flange to move the driven member with the lever when the lever is moved in one direction but not 50 when the lever is moved in the other direction, said gripping member engaging solely said leaf spring and said flange whereby the spring flexes to permit the member to grip and to release said flange, and a member movably secured to a 55 stationary part and so constructed and arranged as to grip said flange to prevent movement of the driven member in one direction.

60 3. A one-way drive device comprising a rotatable driven member, a coaxial oscillatable driving member, a lever drivingly secured to the driving member and pivoted about the axis thereof, a second lever engaging the driven member, resilient means connecting said levers and solely supporting said second lever and holding it so that 65 it will grip said driven member to rotate it with the first lever in one direction but not in the other direction, and means secured to a stationary part and engaging said driven member to prevent rotation thereof in one direction.

70 4. In a one-way drive device having a driven member with a peripheral flange, means for en-

gaging said flange in one direction only, comprising a lever having a notch to receive the flange, said lever engaging the flange at an angle less than a right angle to a tangent at the point of engagement, a leaf spring secured to and carrying said lever, and a mounting for said leaf spring so arranged as to flex the leaf spring in a direction to urge the lever into gripping engagement with the flange.

5 5. A one-way drive device comprising, a driven member, an oscillating driving member, a resilient member attached to said driving member, and a fourth member attached to said resilient member, engageable with said driven member to drive it in one direction but not in the other, said 10 fourth member engaging solely said resilient member and said driven member.

15 6. A one-way drive device comprising a driven member, an oscillating driving member, a resilient member attached to said driving member, and a fourth member attached to said resilient member and solely supported and held in engaging 20 position thereby and engageable with said driven member to drive it in one direction but not in the other.

25 7. A one-way drive device comprising a driven member, an oscillating driving member, a leaf spring attached to said driving member and a third member attached to said leaf spring, engageable with said driven member to drive it in 30 one direction but not in the other, said third member engaging solely said leaf spring and said driven member.

35 8. A one-way drive device comprising a driven member, an oscillating driving member, a leaf spring attached to said driving member, and a third member attached to said leaf spring and solely supported and held in engaging position 40 thereby and engageable with said driven member to drive it in one direction but not in the other.

45 9. A one-way drive device comprising, a driven member, an oscillating driving member, a leaf spring attached to said driving member at one of its ends and extending therefrom, and a third member attached to the free end of the leaf spring and engageable with said driven member to drive it in one direction but not in the other, said third member engaging solely said leaf spring and said driven member.

50 10. A one-way drive device comprising, a driven member, an oscillating driving member, a leaf spring attached to said driving member at one of its ends and extending therefrom, and a third member attached to the free end of the leaf spring and engageable with said driven member to drive it in one direction but not in the other, said third member being solely supported and held in engaging position by the spring.

55 11. A one-way drive device comprising, a driven member having a peripheral flange, an oscillating driving member, a resilient member attached to said driving member at one of its ends and extending therefrom, a fourth member attached to the free end of said resilient member, having a notch adapted to receive said flange, said resilient member solely supporting and holding said fourth member so that the edges of said notch engage said flange when the driving member moves in one direction and release said flange when the driving member moves in the other direction.

65 70 GEORGE W. GRISDALE.
